UNITED STATES PATENT OFFICE.

SOLOMON P. BENTLEY, OF SPRINGFIELD, MINNESOTA, ASSIGNOR OF THREE-FOURTHS TO JOHN S. COLOMY AND HALFDON R. SOOT, OF SAME PLACE, AND BURTON TYLER, OF AMBOY, MINNESOTA.

CAR-COUPING.

SPECIFICATION forming part of Letters Patent No. 391,732, dated October 23, 1888.

Application filed June 30, 1888. Serial No. 278,611. (No model.)

To all whom it may concern:

Be it known that I, SOLOMON P. BENTLEY, a citizen of the United States, residing at Springfield, in the county of Brown and State of Minnesota, have invented a new and useful Improvement in Car-Couplers, of which the following is a specification.

The invention relates to improvements in car-couplers; and it consists in the construction and novel combination of parts hereinabove described, illustrated in the drawings, and pointed out in the appended claims.

Figure 1 of the drawings represents a perspective view of the end of a car having a draw-head illustrative of the invention attached. Fig. 2 represents a plan view of the draw-head with the locking-cylinder detached. Fig. 3 represents a perspective view of the cylinder. Fig. 4 represents a sectional view of the draw-head, the parts being in position to uncouple.

Referring to the drawings by letter, A designates the end of a car, having the recessed draw-head B attached. The said draw-head is of general cylindrical shape, and its mouth or opening b is oval and extends vertically, as shown in Fig. 1. The recess b' within said draw-head is cylindrical and forms a seat for the coupling-cylinder, hereinafter described.

C is a transverse rectangular opening in the top of the draw-head and communicating with the recess b', and D is a similar but narrower opening in the bottom of said draw-head.

E is a cylinder having a twisted bore, e, which cylinder is seated and partially turns in the recess of the draw-head. The said bore is oval in cross-section and registers normally with the opening b, having its diameter equal to that of said opening.

F is a curved arm projecting from said cylinder through the opening D, and provided with an adjustable weight, f, that causes the opening b and the adjacent orifice of the bore e to register.

G is a coupling-link bar, having the barbed or lance-shaped heads g, the points g' of which stand vertically. When one of said heads enters the draw-head and coupling-cylinder, it rotates the latter partially till it passes therethrough. The cylinder then falls to its nor-

mal position, actuated by the described arm 50 and weight, and the points g' catch against the inner end of the cylinder, the inner orifice, g², of which stands transversely to the opening b when the latter registers with the outer opening thereof.

H H are bearings secured within the front and rear ends of the opening C, and I is an upstanding weighted bar having trunnions i on its lower end journaled in said bearings. k is a shoulder on the lower end of said arm, 60 which shoulder bears on the arm K, rising from the coupling-cylinder.

L is a shaft journaled on a proper part of the end of the car, having the crank l on its outer end, to the outer side of the car, and the arm l' on its inner end.

M is a cord or chain connecting the end of the arm l' and a proper part of the bar I, so that when the said shaft L is turned by means of the crank l the bar I bears on the arm and 70 turns the coupling-cylinder in such position that the inner orifice of the same assumes a vertical position and registers with the entrance-opening of the draw-head, permitting the link-bar to escape.

Having described my invention, I claim—

1. The combination of the draw-head having an elliptic entrance-opening, the locking-cylinder arranged in the draw-head and having a twisted bore and provided with an upwardly-projecting arm, K, the bar I, pivotally mounted on the upper side of the draw-head and bearing on the arm K, and mechanism for operating said bar I, as set forth.

2. In a car-coupler, the combination of the draw-head having an elliptic vertically-extended entrance-opening and provided with the openings C and D, the locking-cylinder having a twisted bore and provided with an arm, K, projecting through the upper opening, C, of the draw-head, the pivoted weighted bar I, having a shoulder, k, to bear on said arm K, the crank-shaft journaled on the end of the car and provided with an outstanding arm, l', and the cord M, connecting the arm l' 90 and the weighted bar, substantially as specified.

3. In a car-coupler, the combination of the

draw-head having an elliptic vertically-extended entrance-opening and provided with the opening D in its lower side, the locking-cylinder provided with a twisted bore having 5 a diameter equal to that of the entrance-opening of the drum-head, and the weighted arm projecting from said cylinder down through the opening D and causing the outer orifice of the bore of said cylinder to normally register

with the entrance-opening of the draw-head, to substantially as described.

In testimony that I claim the foregoing as my own I have hereto affixed my signature in presence of two witnesses.

SOLOMON P. BENTLEY.
